UNITED STATES PATENT OFFICE.

EMMETT W. STULL, OF MILWAUKEE, WISCONSIN, ASSIGNOR TO ALLIS-CHALMERS COMPANY, A CORPORATION OF NEW JERSEY.

CONTROLLER.

1,012,027.

Specification of Letters Patent. Patented Dec. 19, 1911.

Application filed March 31, 1910. Serial No. 552,694.

To all whom it may concern:

Be it known that I, EMMETT W. STULL, a citizen of the United States, residing at Milwaukee, in the county of Milwaukee and State of Wisconsin, have invented certain new and useful Improvements in Controllers, of which the following is a full, clear, and exact specification.

This invention relates to electric controllers such, for example, as are employed in connection with electric motors, and especially to arrangements for preventing arcing at the controller contacts.

As is well known, there is considerable arcing in a controller when it is shifted backwardly from its first operative position to off position, and in a series parallel controller when the latter is shifted forwardly to change the motors from series relation to parallel relation, or when shifted backwardly to change the motors from parallel relation to series relation.

The object of the present invention is to avoid arcing at the controller contacts and to provide improved means whereby the circuit of the motor or other translating device can be opened exterior to the controller before the circuit is opened at the controller. I accomplish the above object in a very effective manner by employing in combination with the controller, which may be of any suitable or preferred type, a switch having an operating magnet which is connected to the controller in a manner such that the circuit of the magnet is opened and the magnet is deenergized so as to permit the switch to be opened, before the motor or main circuit is opened at the controller. Preferably, the switch which is connected in series with the motor is normally biased toward open position, and is closed and retained in closed position by the magnet which is connected to suitable controller contacts, which cooperate with other contacts so arranged that the magnet is deenergized, and the switch is opened in every instance before the circuit of the motor or other translating device is opened at the controller.

The invention may be further briefly summarized as consisting in certain novel combinations and arrangements of parts which will be described in the specification and set forth in the appended claims.

The single figure of the drawing shows

diagrammatically the preferred embodiment of my invention.

The controller C shown in this figure may be of any desired type, but, as here shown, is a series parallel controller for two electric motors M and M'. The controller includes stationary contact fingers 13 to 24, inclusive, which cooperate with different contact segments 25 of the controller drum so as to vary the current supplied to the motors. The controller has twelve operative positions 1 to 7, and as it is moved between positions 1 to 7, the resistance R in the motor circuit is varied with the motors connected in series, and as it is moved from positions 8 to 12, the resistance R is varied with the motors connected in parallel, the motors being changed from series relation to parallel relation when the controller is moved from position 7 to position 8.

To avoid arcing at the contacts of the controller, I employ exterior to the controller a switch S having terminals 26 and 27 connected respectively to the trolley 28 and to a contact finger 29 of the controller, this contact finger being adapted to engage a segment 30 when the controller is moved between positions 1 to 7, and to engage a segment 31 when the controller is moved between positions 8 to 12. This switch S is biased toward open position and is closed and retained in closed position as long as current is being supplied to the motors by means of a magnet including a coil 32 having a rather high resistance circuit which is adapted to be opened and closed so as to deenergize or energize the magnet by special contacts provided in the controller.

In order that the magnet may be energized and deenergized at the proper times, I provide suitable contacts in the controller and connect these contacts to the source of current supply and to the magnet coil in a manner such that when the controller is moved from off position to first operative position, or is moved from position 7 to 8, a shunt circuit is momentarily established through the magnet coil and around the switch S and controller C so as to energize the magnet and permit the switch to be closed, and after the switch is closed and current is supplied to the motors, the magnet coil is in series with the switch and in shunt to the controller. This last

named shunt circuit remains established or closed until it is broken at the controller so as to permit the switch to open just before the motor circuit is broken at the controller, either in moving the latter to off position or in changing the motors from parallel relation to series relation, or from series relation to parallel relation. For this purpose, I provide two additional contact fingers 33 and 34 and connect the finger 33 by a conductor 35 to the conductor connected to the trolley 28, and to the contact finger 34 I connect one terminal of the magnet 32, the other terminal of the latter being connected to ground G. I also provide on the controller drum short segments 36, 36^a, and 37 which are adapted to engage finger 33, and comparatively long segments 38 and 39 which are adapted to engage finger 34. The segments 36 and 38 are arranged slightly in the rear of the segments which are adapted to engage fingers 18 and 29 respectively, so that when the controller is moved from off to first operative position, and after the fingers 29 and 18 are engaged by the segment 30 and one of the segments 25 respectively, fingers 33 and 34 will be engaged by the segments 36 and 38 so as to complete the shunt circuit through the conductor 35, and magnet coil 32 to ground, and when the controller is moved from first operative position to off position, the segments 36 and 38 will leave or be separated from the contact fingers 33 and 34 prior to the separation of the segments 25 and 30 from the fingers 18 and 29. The segments 36^a and 38 terminate before the segment 30 so that in moving the controller forwardly from position 7 so as to place the motors in parallel relation, the segments 36^a and 38 are moved out of engagement with the fingers 33 and 34 before the segments 25 and 30 are separated from the fingers 14 and 29. In a like manner, the contact segments 37 and 39 are placed slightly rearwardly of the segments which cooperate with or engage the contact fingers 14 and 29 to reestablish the motor circuit with the motors connected in parallel, with the result that in moving the controller forwardly to position 8, the segments 37 and 39 will engage the fingers 33 and 34 so as to close the motor circuit at the switch S after the motor circuit is closed at the controller, and in moving the controller backwardly from position 8, the segments 37 and 39 will be separated from the fingers 33 and 34 so as to effect the opening of the switch S before the motor circuit is opened at the controller in changing the motors to series relation. It will be seen therefore that when the controller is moved forwardly from off position, a shunt circuit is momentarily established around the switch and the controller so that the magnet coil is energized

and the switch is closed, permitting the current to be supplied through the switch and controller to the motors, and when the controller is moved from position 1 to position 2, and in fact, when moved from position 1 to position 7, the magnet coil is connected in series with the switch and in shunt with the controller, this change taking place as soon as the segment 30 moves out of engagement with the contact finger 33. When the controller is moved from position 7 to position 8, the shunt circuit of the magnet coil around the controller is broken, and the switch is opened before the motor circuit is broken at the controller. When the controller is moved to position 8, the shunt circuit about the switch and controller is again momentarily completed, so that the magnet is energized, and the switch is closed, and when the controller is moved from position 8 to position 12, and after the segment 37 is moved from the finger 33, the shunt circuit about the controller is again established and remains established so as to hold the switch closed until the controller is moved backwardly, and the segments 37 and 39 are moved beyond the fingers 33 and 34, this taking place just before the motor circuit is broken at the controller when moved from position 8 to position 7. When the controller reaches position 7, in its backward movement, the magnet is again energized by the engagement of the segments 36^a and 38 with the fingers 33 and 34, causing the shunt circuit to be momentarily completed through the magnet coil around the switch and controller. The shunt circuit through the magnet coil around the controller then remains established until position 1 is reached, and just before the controller is moved to off position, the magnet circuit is broken and the switch is opened before the motor circuit is broken at the controller. If desired, a blow-out magnet 40 may be employed in connection with the switch S, and preferably the conductor 35 contains a switch 41, and a fuse 42.

I do not desire to be confined to the exact arrangements shown, but aim in my claims to cover all modifications which do not involve a departure from the spirit and scope of my invention.

Having thus described my invention what I claim is:

1. In combination, a motor, a motor circuit, a controller, a switch in the motor circuit, and an operating magnet connected in different ways at different times to said switch and also connected to the controller in a manner such that its circuit is opened before the motor circuit is opened at the controller.

2. In combination, a translating device, a controller therefor, a switch in the circuit of the translating device, and a magnet

- adapted to be connected in different ways with respect to said switch and which when energized retains the switch in closed position, and which is connected to the controller in a manner such that its circuit is opened before the circuit of the translating device is opened at the controller.
3. In combination, a motor, a motor circuit, a motor controller, and a switch in series therewith and normally biased toward open position, a magnet connected in a certain manner with respect to said switch for closing the switch and in a certain position connected in another manner with respect to said switch for holding it in closed position, said magnet being connected to the controller in a manner such that it is de-energized before the motor circuit is broken at the controller.
4. In combination, a motor, a motor circuit, a motor controller, a switch in series therewith and normally biased toward open position, and a magnet for retaining the switch in closed position, said magnet being connected to the controller in a manner such that its circuit is broken and the switch is opened before the motor circuit is opened at the controller during either forward or backward movement thereof.
5. In combination, a translating device, a controller, a switch in the circuit of the translating device, and a magnet which when energized retains the switch in closed position, the coil of the magnet being connected at different times in different ways with respect to said switch and also connected to the controller in a manner such that it is connected in shunt to the controller when current is supplied to the translating device, and has its circuit opened before the circuit of the translating device is opened at the controller.
6. In combination, a motor, a motor circuit, a motor controller, a switch in series therewith and normally biased toward open position, and a magnet connected at different times in different ways with respect to said switch for closing the switch and for holding it in closed position, the coil of
- said magnet being connected to controller 50 contacts in a manner such that when current is supplied to the motor, said coil is in a shunt circuit about the controller, and before the motor circuit is broken at the controller said shunt circuit is broken and the 55 magnet is deenergized so as to permit the switch to be opened.
7. In combination, a translating device, a controller, a switch in the circuit of the translating device, and a magnet which 60 when energized retains the switch in closed position, the coil of said magnet having suitable connections with the controller, and with the source of current supply so arranged that before the circuit of the translating device is broken at the controller, the circuit of the coil is broken at the controller, and when the controller is moved forwardly or backwardly so as to close the circuit of the translating device at the controller and then vary the current supplied to the translating device, the coil of the magnet is first connected in shunt to the switch and controller so as to energize the magnet and close the switch and is then 70 connected in series with the switch and in shunt to the controller until the circuit of the coil is broken at the controller.
8. In combination, a translating device, a resistance, a controller having a drum 80 adapted to cut said resistance into and out of circuit, a switch in the circuit of the translating device, and a magnet which when energized retains the switch in closed position, the coil of the magnet being connected to the controller drum in a manner such that it is connected in shunt to the controller when current is supplied to the translating device, and has its circuit opened before the circuit of the translating device 85 is opened at the controller.

Milwaukee, Wis., March 19, 1910.

In testimony whereof I affix my signature, in the presence of two witnesses.
